MARCUS B. BEHRMAN, OF BROOKLYN, NEW YORK, ASSIGNOR TO LOX SEAL CORPORATION,
OF BROOKLYN, NEW YORK, A CORPORATION OF NEW YORK

PILE WIRE

Application filed December 8, 1930. Serial No. 500,704.

My present invention relates generally to a pile wire and more particularly to an arrangement for permitting the pile wire to operate more efficiently and with less difficulty during the weaving process.

5 I have illustrated my invention in the drawing and herein disclose it as embodied in a pile wire having associated therewith a blade holder for cutting the pile because it is in this relationship that my invention will be most frequently employed. It will be understood, however, that as to the broader phases of 10 my invention, it is not to be limited to such character of pile wire unless the language specifically calls for such limitation.

15 A great deal of difficulty has been encountered in the employment of pile wires because the withdrawal of the pile wire into the hopper is resisted by the friction developed between it and the warp threads and 20 because of the fact that this friction engenders a great deal of heat so that the pile wire will tend to heat up and possibly effect the fabric being woven.

25 Furthermore, in the shedding operation, the warp threads are crossed at each side of the pile wire and there will therefore be a tendency for the warps to pack at the opposite sides of a pile wire and this serves still further to increase the difficulties.

30 It is one of the objects of my invention to so devise and construct a pile wire as to reduce the amount of friction and therefore decrease the resistance offered to the withdrawal of the pile wire by the warp threads and this, I accomplish by reducing the area 35 of the surface contact between the pile wire and the warp threads without at the same time decreasing the size of the pile wire.

40 It is another object of my invention to so arrange and construct the pile wire as to provide specifically for the fact that the material bulks where the warp threads cross and this I accomplish by decreasing the thickness 45 of the pile wire along the areas which correspond more or less to the points where the crossing takes place.

In attempting to overcome the difficulty of the resistance by the warp threads to the 50 withdrawal of the wire by lubricating the

wire, I have found that the pile wires, as at present constructed, are inefficient for this purpose because of the fact that the lubrication does not stick to the pile wire sufficiently long to accomplish its purpose.

55 It is one of the further objects of my invention to so arrange and construct the pile wire that the lubrication associated therewith be carried with the pile wire so as to more sufficiently serve the purpose intended and this I accomplish by so contouring certain selected walls for the pile wire that the lubrication can be simply and sufficiently received within those walls, and held therewithin for the purpose of serving its intended 60 purpose throughout the complete withdrawal 65 of the pile wire.

In the illustrated embodiments of my invention herein disclosed, I attain all of the above objectives by decreasing the thickness 70 of the pile wire intermediate its top and bottom so as not only to decrease the surface contact between the warps and the pile wire, but by properly selecting the location of this decreased thickness to make provision additionally for the retention by the pile wire of 75 lubricant associated therewith.

For the attainment of these objects and such other objects as may hereinafter appear or be pointed out, I have illustrated embodiments 80 of my invention in the drawing, wherein—

Figure 1 is a side elevational view of a pile wire embodying my invention and having a blade holder associated therewith, and the pile wire broken away intermediate its 85 ends;

Figure 2 is a view similar to that of Figure 1 on an enlarged scale, of the spoon end of the pile wire;

Figure 3 is a section taken on line $a-a$ of 90 Figure 1;

Figure 4 is a section similar to that of Figure 3 of a modification;

Figure 5 is a section similar to that of 95 Figure 3 of a further modification;

Figure 6 is a section similar to that of Figure 3 of a still further modification; and

Figure 7 is a top view upon an exaggerated 100 scale of a portion of the pile wire operatively

associated with a series of warp loops during the cutting of the latter.

Before proceeding to describe my invention I will premise that where pile wires are to merely form the loops, they have no cutting implement associated therewith and where they are intended to form the loops and then cut through the loops, they have associated with them cutting edges which function upon the retraction of the pile wire to cut through the loops formed thereabout. I have illustrated my invention as embodied in a pile wire having a cutting attachment associated therewith (first) because this is the more common form and (secondly) because the embodiment of my invention in a pile wire having a blade holder associated therewith gives rise to some additional problems which the further development of my invention has attempted to solve. While, therefore, I have illustrated and herein described my invention as embodied in such a type of pile wire, it will be understood, of course, my invention is generally of generic application unless the language of the claims specifically sets forth otherwise.

I will further premise that the weaving arts have developed to a point where the broad looms are becoming larger and larger to weave fabrics, such as carpets, of increased width and that therefore, the pile wires employed in such looms are getting longer and longer until pile wires are now being used which are almost 20 feet in length. The increase in the length of pile wire has necessitated the increase in the other dimensions of the pile wire so that not only have factors which were hitherto of minor importance become of major importance, but wholly new factors have arisen. For example, the surface areas in contact with the loops have increased, thus giving rise to increased resistances and increased heating of the pile wire. The invention which I will now describe is directed to meeting these problems.

In Figure 1 of the drawing is illustrated a pile wire made up of the wire proper 10, the head 11, and the spoon end 12. Associated with the spoon end is a blade holder 13. The blade (not shown) is intended to be received in a slot the blade holder 13 and held therein by the lug 14 and other means which will not be described herein because they are to be made the subject of a separate application.

The pile wire 10 is shown in cross section in Figure 3, as having its upper and lower surfaces 15 and 16 rounded and as merging into the side walls 17 and 18, thus giving to the pile wire a generally oval shape for eliminating as far as possible any sharp edges which might act adversely upon the fabric.

It will be understood that the pile wire of Figure 3 is of rather unusual length, height and thickness because it is to be employed in a very large broad loom. I have thinned

out the side walls 17 and 18 of the pile wire of Figure 3 from a point adjacent the upper wall 15 to a point adjacent the lower wall 16 so as to provide the concavities 20 and 21, which gradually taper outwardly and merge into the upper and lower portions of the side walls 17 and 18.

The concavities 20 and 21 are so positioned in the pile wire that they will be more or less in registration with the point where the warp threads cross to complete the loops, and I have attempted to show this in Figure 7 more or less diagrammatically.

As a result of this arrangement, the space between the adjacent pile wires is increased materially between the concavity 21 on one pile wire and the concavity 20 on the next adjacent pile wire to the right in Figure 3, so as to allow for the packing tendency of the loops where they cross.

In the weaving operation when the wefts are beaten up, the pile wire and the warp sections therebetween will be closely compacted and the withdrawal of the pile wires, particularly where they are of the large size as illustrated in Figure 3 will meet with such a resistance due to the friction between the warp sections and the side walls 17 and 18, that it has become a serious problem in the employment of pile wires in looms of this type. The provision of the concavities 20 and 21 attains the objective of reducing this friction factor to a minimum.

Furthermore, not only are broad looms presented with a problem of providing for these increased resistances, but the friction or the resistances engenders heat which heats up the wire to points where frequently damage is done to the fabric. The provision of the concavities 20 and 21 and the selection of their location, I have found has reduced this heating factor to a minimum (first) because of the generation of heat is greatly reduced, and (secondly) is taken up by the portions of the pile wire between the concavities 20 and 21 so as to still further reduce the heating factor.

In addition the grooves 20 and 21 (see Fig. 1) reduce the weight of the pile wire without substantially decreasing its rigidity.

The side walls 17 and 18 are each made up of three sections, for example, the side wall 17 is made up of the upper surface 17', the concave section 21 and the lower portion 17''. So also the outer side wall 18 is made up of the upper section 18', the concavity 20 and the lower section 18''.

The surface contact with the pile wire will be made by the warp sections only with the side wall portions 17' and 18' at the top and the side wall portions 17'' and 18'' at the bottom. This allows for a differential in friction action which attains my objectives even beyond what would be the case if the side wall sections of the pile wire 17' and 18'

17" were contiguous and continuous. The location of the concavity therebetween gives this added advantage.

In the actual operation of pile wires in the loom, the pile wires are held in a hopper and are thrown across the loom successively to form the loops as the successive sheds are formed. Where I have attempted to lubricate the pile wires, as for example, by having their side walls contact with a lubricant in the hopper as the pile wires are thrown across the loom, I have found that the lubricating action is inefficient because of the tension of the warp sections against the side walls for substantially their entire length. The presence in the pile wire of concavities 20 and 21 herein described not only enables the pile wire to pick up the lubricant in these concavities and feed this lubricant to sections 17' and 17" on one side and to the sections 18' and 18" on the other side, but it also serves to retain the lubricant because of the facts that the warp sections are stretched across the concavities. The lubricating action is materially assisted by the minimization of the heating of the pile wire as already above referred to.

I have found that by this arrangement all of the problems hitherto attendant upon the use of the pile wire referred to, have been either wholly eliminated or minimized to an extent where they are no longer serious problems.

My arrangement, while particularly intended for pile wires of the large size and of the character described in connection with Figure 3, has proven to be so advantageous that I have found that it serves admirably with pile wires of smaller size and less height and this I have attempted to show in Figure 4 of the drawing where a pile wire 30 is shown of the smaller type, provided with the concavities 31 and 32 generally like the concavities 20 and 21 of Figure 3, except that here the concavities will be of less height due to the fact that the pile wire also is of less height and will be therefore of greater relative depth.

In Figure 5, I have shown a further development of my invention wherein a pile wire 35 of the character shown in Figure 2 is provided with a pair of grooves on each face. In this pile wire of Figure 5, the side wall to the right is made up of the flat sections 36, 28 and 40 in between which are formed the grooves or concavities 37 and 39. The side wall on the left is similarly formed of the flat sections 41 and 43 and 45, separated by the grooves 42 and 44.

In Figure 6 I have shown an embodiment which is intended to allow of the greater variation either in the depth of the concavities or in the thickness of the pile wire, and in this figure the pile wire 50 has its side wall on the left formed of the sections 51,

53 and 55 between which are formed the grooves or concavities 52 and 54. The side wall on the right is made up of the upper section 56 and lower section 58 between which is formed the enlarged groove or cavity 57. It will be observed that the grooves 52 and 54 on one side are in staggered relation to the grooves 57 on the other side.

It will be understood that the pile wire of Figures 3, 4, 5 and 6 can have the grooves or concavities formed therein by a rolling process or the like during the process of manufacture of the pile wire or can have these grooves formed therein after the pile wire has been formed.

In Figure 1, I have shown the groove 20 as in the form of a continuous groove extending for the full length of the pile wire. It will be understood that the general purpose of my invention may be attained without making this groove exactly as shown in the drawing. For example, it may be discontinuous.

Referring back to the Figures 1 and 2 of the drawing in which a blade holder is shown as associated with the pile wire, it will be understood that the blade holder portion is formed separate and apart from the pile wire and is then associated with the pile wire as by a welding operation and the line A—A in each of these figures is intended to represent approximately the line of the weld. In the association of the pile wire with the blade holder 13, I have found it advisable to extend the grooves or concavities 20 and 21 into the blade holder and this I have done in a manner which causes this groove not only to taper upwardly and downwardly but also to taper forwardly to form the conically concave section 60. In this manner the presence of any abrupt shoulders between the groove portions 20 and 21 and the rest of the pile wire thereabout is eliminated.

Having thus described my invention and illustrated its use, what I claim as new and desire to secure by Letters Patent is—

1. A pile wire bar having spaced warp section engaging portions defining a side wall thereof and a groove therebetween.

2. A pile wire bar having spaced engaging portions defining the side walls thereof and grooves therebetween.

3. A pile wire bar having spaced engaging portions being substantially in the same plane, the material between said sections being depressed.

4. A pile wire comprising an elongated bar of metal generally oblong shaped in cross section and having grooves on opposed faces thereof.

5. A pile wire comprising an elongated bar of metal generally oblong shaped in cross section and having a groove on a face thereof and directed generally parallel to the major axis of the oblong cross section.

6. A pile wire comprising an elongated bar of metal having grooves on opposed faces and directed generally parallel to the major axis of the bar.

7. A pile wire bar having spaced warp section engaging portions on a side wall thereof and a groove therebetween, said groove tapering outwardly at its upper and lower ends and merging into said portions.

8. A pile wire bar having spaced warp section engaging portions on a side wall thereof and a groove therebetween, said groove tapering outwardly at its front and upper and lower ends and merging into said portions and the spoon end of the pile wire.

In witness whereof I have signed and sealed this specification.

MARCUS B. BEHRMAN.
